(57) **CLAIM**

The ornamental design for a beauty instrument, as shown and described.

DESCRIPTION

FIG. 1 is a front, right and bottom perspective view of a beauty instrument, showing my new design;

FIG. 2 is a rear, left and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front, right, and bottom perspective view of the beauty instrument shown in a state of use; and,

FIG. 10 is a bottom plan sectional view shown from line 10-10 in FIG. 3 thereof.

The broken lines shown in the drawings illustrate portions of the beauty instrument that form no part of the claimed design.

1 Claim, 10 Drawing Sheets
